UNITED STATES PATENT OFFICE.

LEVI F. TORREY, OF CLEVELAND, OHIO.

SPRING-FITTING MACHINE.

1,253,304.

Specification of Letters Patent. Patented Jan. 15, 1918.

Application filed April 1, 1916. Serial No. 88,249.

To all whom it may concern:

Be it known that I, Levi F. Torrey, a citizen of the United States, and resident of Cleveland, in the county of Cuyahoga and State of Ohio, have invented certain new and useful Improvements in Spring-Fitting Machines, of which I hereby declare the following to be a full, clear, and exact description, such as will enable others skilled in the art to which it appertains to make and use the same.

The objects of the invention are to provide an improved and efficient form of spring fitting machine particularly adapted to shaping and tempering the curved springs of automobiles.

The invention particularly includes means for gripping or pinching springs at their longitudinal margins in a manner corresponding to the work ordinarily effected by hand tools or tongs, to give the final shape to the same.

It includes a tempering bath in which the springs are immersed while rigidly held in predetermined positions by their margins, and in which the body of each spring is thereby made accessible to the action of the tempering fluid.

It also includes means for rigidly engaging the springs on their sides and edges whereby when tempered they will become set in the finished form without subsequent warping or buckling and in this manner accomplishing the work heretofore done by hand and reducing the cost of the production of the springs.

The invention further includes the use of forming fingers having adjustable gripping tips, spaced apart to permit free ingress of the tempering fluid and means for adjusting the same.

It includes means for shaping peculiar forms of springs, especially those having re-entrant angles, which have hitherto been shaped only by hand.

It further includes the combination and arrangement of parts and construction of details hereinafter described and specifically pointed out in the claims.

In the accompanying drawings Figure 1 is a plan view of the machine; Fig. 2 is a longitudinal section thereof; Fig. 3 is an enlarged section showing the central portion of Fig. 2; Fig. 4 is a perspective view of the depending portions of the gripping and

pinching fingers; Fig. 5 is an enlarged plan of one spring showing the pivoted extremities of the finger bars which form the angle therein; Fig. 6 is a transverse section enlarged of one of said finger bars; Fig. 7 is a side elevation of a finger bar showing a pivoted terminal therefor, and a pivoted sliding accessory finger tip secured adjustably to the bar.

In these views A is the bed plate having a platform B upon which bed plate opposed series of shaping fingers C, C' are adjustably mounted.

Upon one end of the machine the series of fingers C, C' rest directly upon the platform, and do not move except as adjusted by set screws c, c'. Cap plates D, D, secured to the bed plate serve as guides and retaining means therefor.

Upon the other end of the machine the series of fingers C', C' are adjustably mounted, by means of set screws c', c' upon a movable bed plate E, which slides horizontally upon brackets F and is reciprocated to alternately move the fingers C' to and from the opposed fingers C, by suitable power applying means such as the toggle links G, G, and operating link H and crank I rotated by means of a lever J.

Beneath the shaping ends of the opposed series of fingers is positioned the tank K filled with tempering fluid such as oil, and means are shown such as a hydraulic or pneumatic cylinder L and piston M for raising the entire tank to immerse the fingers and the spring plates N and pattern O inclosed between them.

To facilitate this action the forming extremities c', c' of the opposed series are depressed below the bed plate so that when the oil tank is raised the fingers and work will be inclosed by the tempering fluid.

In Figs. 2, 3, and 4 this structure is shown where A' is a depressed horizontal grating which may be integral with the bed plate, 100 and upon which the lower edges of the spring plate N and pattern O are supported.

This grating gives free access for the oil to all sides of the spring plate.

Each finger in both series is provided with a horizontal projecting member c' at its lower end. These projecting members engage the spring and pattern on opposite sides and exert a pinching action upon the lower margins thereof.

Spaced vertically above these projecting members are similar narrow projecting members c^5 , vertically adjustable upon the depending extremities of the opposed series 5 of fingers by means of slotted stems c^6 and studs c^7 .

These extremities grip or pinch the upper margins of the spring plates and pattern and exert a pressure thereon corresponding to that of the lower projections c^4 upon the lower margins of the spring and pattern.

Each upper projecting member upon the stationary series of fingers is provided with 15 an extended shoulder c^8 which extends over the pattern O and rests upon the upper edge of the spring plate N, thus preventing the plate from warping in the direction of its plane.

20 The spring is thus embraced upon sides and upper edge by rigid finger members and forced into close engagement with the depending grating at its lower edge, and in this position while pinched into final shape 25 by the pressure between the stationary and movable series of fingers, the tempering tank is elevated until the platform and fingers inclosing the spring plate and pattern are immersed in the tempering fluid, which 30 sets the spring until it will retain its fitted shape after it is released from the fingers.

In Fig. 5 a bow spring of peculiar shape is shown having deeply indented angular recesses R, R. These are formed by means 35 of the pivoted tips or projecting terminal members R', R' upon suitably positioned fingers which enter the recesses and force the spring therein.

These tips are adjustably secured in any 40 desired inclined position by means of key ways r, r, and keys r', r' so that they will exert a thrust in precisely the right direction to form the required angular recess.

Having described the invention, what I 45 claim as new and desire to secure by Letters Patent is:

1. In a machine for fitting vehicle springs, a frame, a series of stationary shaping fingers and a series of movable fingers opposed thereto, a depressed platform upon which the spring rests, depressed engaging extremities for the lower margins of said spring, and upon the extremities of said series of fingers, engaging means for the upper 55 margins of said spring, said upper engaging extremities vertically adjustable upon said fingers, and a tank of tempering fluid

in which said finger extremities, depressed platform and spring are immersible.

2. In a machine for fitting vehicle springs, 60 a frame, a series of stationary shaping fingers and a series of movable fingers opposed thereto, a depressed platform upon which the spring rests, depressed engaging extremities for the lower margins of said spring, and upon the extremities of said series of fingers, engaging means for the upper margins of said spring, said upper engaging extremities vertically adjustable upon said fingers, and a tank of tempering 70 fluid in which said finger extremities, depressed platform and spring are immersible, and means for reciprocating the movable series of fingers and for elevating said tank.

3. In a machine for fitting vehicle spring 75 plates, a frame or bed plate, a series of shaping fingers, stationary thereon, an opposed series of fingers movable upon the bed plate to and from the first mentioned fingers, depressed extremities for the series of 80 fingers, a depressed support for the spring plate engaging means for the lower margins of said spring attached to the depressed extremities of said opposed series of fingers, engaging means for the upper margins of 85 said spring, and vertically adjustable upon said depressed extremities, and extended members upon some of the stationary fingers for engaging the upper edge of said spring.

4. In a machine for fitting vehicle spring 90 plates, a frame or bed plate, a series of shaping fingers, stationary thereon, an opposed series of fingers movable upon the bed plate to and from the first mentioned fingers, depressed extremities for the series of 95 fingers, a depressed support for the spring plate, engaging means for the lower margins of said spring attached to the depressed extremities of said opposed series of fingers, engaging means for the upper margins of 100 said spring, and vertically adjustable upon said depressed extremities, and extended members upon some of the stationary fingers for engaging the upper edge of said spring, means for operating said series of movable 105 fingers, a tank containing tempering fluid, and means for elevating said tank to immerse said spring plate therein.

In testimony whereof, I hereunto set my hand this 24th day of March, 1916.

LEVI F. TORREY.

In presence of—

RALPH W. JEREMIAH,
Wm. N. MONROE.
